US0D1080630S

(12) **United States Design Patent** (10) **Patent No.:** **US D1,080,630 S**
(45) **Date of Patent:** **** Jun. 24, 2025**

(54) **CASE FOR ELECTRONIC DEVICE**

- (71) Applicant: **Samsung Electronics Co., Ltd.**, Suwon-si (KR)
- (72) Inventors: **Jisu Hwang**, Suwon-si (KR); **Namhyun Kang**, Suwon-si (KR); **Mingeun Kim**, Suwon-si (KR); **Minah Koh**, Suwon-si (KR)
- (73) Assignee: **SAMSUNG ELECTRONICS CO., LTD.**, Gyeonggi-Do (KR)

(**) Term: **15 Years**

(21) Appl. No.: **29/902,357**

(22) Filed: **Sep. 12, 2023**

(30) **Foreign Application Priority Data**

Jun. 13, 2023 (KR) 30-2023-0022404

(51) **LOC (15) Cl.** **14-02**
(52) **U.S. Cl.** **D14/440**

(57) **CLAIM**

The ornamental design for a case for electronic device, as shown and described.

DESCRIPTION

FIG. 1 is a front perspective view of a case for electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion '9' in FIG. 4;

FIG. 10 is an enlarged view of the encircled portion '10' in FIG. 6;

FIG. 11 is an enlarged view of the encircled portion '11' in FIG. 7; and,

FIG. 12 is a rear perspective view of the case for electronic device of FIG. 1 shown in a state of use.

The dash-dash broken lines illustrate portions of the case for electronic device that form no part of the claimed design. The dot-dot-dash broken lines define the boundaries of the enlarged detail views and form no part of the claimed design.

1 Claim, 8 Drawing Sheets
